DISH DRAINER

Michael C. Wilson, Wheaton, Ill., assignor to
Pretty Products, Inc., Coshocton, Ohio

Filed Jan. 15, 1974, Ser. No. 433,552

Term of patent 14 years

Int. Cl. D7—06

U.S. Cl. D7—188

FIG. 1

FIG. 2

FIG. 3

FIG. 5

FIG. 4

FIG. 6

FIG. 1 is a top plan view of a dish drainer, showing my new design.

FIG. 2 is a bottom plan view thereof.

FIG. 3 is a side elevational view as seen along line 3—3 of FIG. 1 on an enlarged scale.

FIG. 4 is a side elevational view as seen along line 4—4 of FIG. 1 on an enlarged scale.

FIG. 5 is a vertical sectional view taken along line 5—5 of FIG. 1 on an enlarged scale.

FIG. 6 is a perspective view of the dish drainer on an enlarged scale with the side walls thereof disposed in assembled relationship.

I claim:

The ornamental design for a dish drainer, substantially as shown and described.
